PICK GUARD FOR GUITAR OR SIMILAR ARTICLE

Richard L. Schneider, Kalamazoo, Mich., assignor to
Norlin Music, Inc., Lincolnwood, Ill.

Filed May 12, 1975, Ser. No. 576,271

Term of patent 14 years

Int. Cl. D17—03

U.S. Cl. D56—1 A

Fig. 5.

Fig. 2.

Fig. 1.

Fig. 3.

Fig. 6.

Fig. 4.

FIG. 1 is a front elevational view of a pick guard for guitar or similar article showing my new design;

FIG. 2 is a side elevational view of the left side thereof;

FIG. 3 is a side elevational view of the right side thereof;

FIG. 4 is a back elevational view thereof;

FIG. 5 is a view of the top end thereof; and

FIG. 6 is a view of the bottom end thereof.

I claim:

The ornamental design for a pick guard for guitar or similar article, substantially as shown and described.
